CLAIM

The ornamental design for a razor handle, as shown and described.

DESCRIPTION

FIG. 1 is a perspective view of a razor handle of the present invention;

FIG. 2 is a back view of the razor handle of FIG. 1;

FIG. 3 is a front view of the razor handle of FIG. 1;

FIG. 4 is a left side view of the razor handle of FIG. 1;

FIG. 5 is a right side view of the razor handle of FIG. 1;

FIG. 6 is a top view of the razor handle of FIG. 1; and,

FIG. 7 is a bottom view of the razor handle of FIG. 1.

The broken lines shown in the drawings illustrate the environment of the razor handle and form no part of the claimed design.

1 Claim, 4 Drawing Sheets
